UNITED STATES PATENT OFFICE.

ALLAN L. McGREGOR, OF DULUTH, MINNESOTA.

AUTOMOBILE-BUFFER.

1,014,713.

Patented Jan. 16, 1912.

Application filed August 27, 1909. Serial No. 514,902.

To all whom it may concern:

Be it known that I, ALLAN L. MCGREGOR,
a citizen of the United States, residing at
Duluth, in the county of St. Louis and State
5 of Minnesota, have invented certain new and
useful Improvements in Automobile-Buf-
fers, of which the following is a specifica-
tion.

This invention relates to buffers for use on automobiles, and has reference more particularly to that type of buffer now extensively employed wherein a horizontally disposed buffer-bar is yieldably mounted upon and in advance of the usual elliptical springs supporting the forepart of the automobile body.

The invention has for its general object to provide a simple and improved device of this type which may be readily attached to 20 automobile frames of varying sizes, and which shall be held securely in operative position, notwithstanding the jar and vibration to which such devices are subjected, which imposes a severe strain upon the at- 25 taching parts.

More specific objects of the invention are, first, to provide an improved construction capable of resisting strains and shocks upon the end portions of the buffer-bar without injury to the latter or to its cushioning and connecting devices; second, to provide a construction adaptable to varying sizes and shapes of frames; and third, to provide a construction wherein the attachment of the rear ends of the cushioning devices carrying the buffer bar may be made either to the forwardly projecting side bars or to the underlying elliptical springs, as may be more convenient in any given case.

40 Other minor objects of the invention will appear from the following description, taken in connection with the accompanying drawings which illustrate one practical form in which the invention may be dressed, and
45 wherein—

40 which
Figure 1 is a top plan view of my im-
proved automobile buffer, showing the same
as mounted on the forward end of the ve-
hicle frame. Fig. 2 is an enlarged cross-
50 sectional view on the line 2—2 of Fig. 1,
looking in the direction indicated by the
arrows. Fig. 3 is an enlarged cross-sec-
tional view on the line 3—3 of Fig. 2, look-
ing in the direction indicated by the arrows.
55 Fig. 4 is a view generally similar to Fig. 3

in cross-section through the plunger rod and elliptical spring in different vertical planes, showing a manner and means of connecting the rear end of the cushioning device to the elliptical spring instead of to the forwardly projecting side bar, as in Figs. 1, 2 and 3; and Fig. 5 is a cross-sectional detail on the line 5-5 of Fig. 4, looking in the direction indicated by the arrows. 65 60

Referring to the drawings, 10 designates the forwardly and downwardly curved end portions of the usual side bars of the frame, to the forward ends of which are pivoted by hinge-bolts 11 the usual elliptic spring sections 12.

13 designates the buffer bar which is in the usual form, the same being directly mounted in collars 14 clamped thereto by screw-bolts 15, each carrying an inwardly projecting hinge-lug 16 that is pivotally connected by a vertical hinge-bolt 17 with a forked hinge-member 18, into the inner end of which is tapped the threaded end of a plunger-rod 19. This latter slidably engages a guide-sleeve 20 which is rigid, and as herein shown, integral, with a bar 21, said bar being provided on its lower side near its front end with a series of holes 22 whereby it is mounted on the hinge-bolt 11 of the spring 12, said bar extending for the most part rearwardly of said hinge-bolt, as shown. Surrounding the plunger-rod 19 between the inner face of the hinge-member 18 and the forward end of the guide-sleeve 20 is a cushioning spring 23; and the plunger rod is confined against accidental retraction by a cotter-pin 24 passed through one of a series of holes 25 in the inner end of the plunger rod. The parts last described 95 unitedly constitute what I term a cushion-

unitely constitute what I term a cushioning device supporting and carrying the buffer bar 13, there being one of such devices mounted upon the hinge-bolt of each spring 12. To the rear end of each bar 21 is connected a link for maintaining the cushioning device in substantially horizontal position, which link may be connected either to the side bar 10 or to the underlying spring 12, preferably the former. In its preferred form, as herein shown, this link consists simply of a rod 26 having a horizontally bent end portion 27 (Fig. 4) that is threaded and loosely engages an internally threaded hole 28 in the rear end of the bar 21; 110

such threaded connection affording a flexible joint and at the same time permitting a limited degree of adjustment of the link 26 laterally of the members 10 and 12. The 5 opposite end portion of said link 26 is also threaded; and, where the connection is to the side bar 10, as shown in Figs. 1, 2 and 3, this upper threaded end screws into the internally threaded head of an eye-bolt 29, 10 which latter is adjustably secured by nuts 30 and 31 (Fig. 3), to and through the side bar 10, or to and through one of the vertical flanges thereof in the case of a hollow or channeled side bar, as shown. This construction affords a connection that is adjustable both vertically and horizontally, and is preferred for that reason. In this 15 connection it may be mentioned that a series of pivot holes 22 permit of adjusting the position of the buffer bar to a greater or less extent in advance of the forward end of the vehicle; and they may be made of varying sizes, as shown, to adapt the device to varying sizes of pivot-bolts 11 without requiring 20 alteration to secure a fit.

Where the rear end of the cushioning device is attached to the spring 12, the construction is preferably that shown in Figs. 4 and 5; each end or link 26 being swung 25 downwardly and connected at its lower end with the lower jaw 32 of a clamp member, this latter comprising said jaw 32, vertical eye-bolts 33, and an upper clamp jaw in the form of a bolt 34 connecting the upper ends 30 of said eye-bolts; a saddle member 35 carrying a rubber cushion 36 being preferably superposed on the lower jaw 32 to secure a tight clamping effect not liable to be loosened by vibration. To avoid interference with 35 the free action of the spring 12, the lower end of the link 26 has a swiveling connection with the jaw 32 of the clamp, the same comprising a transversely apertured wrist-pin 37 formed with an integral internally threaded eye 38 engaging the link 26, and a socket member 39 formed on one end of the jaw 32 receiving said wrist-pin, said socket member being provided on opposite sides with transverse slots 40 adapted to 40 accommodate a cotter-pin 41 that extends through said slots and through the aperture of the wrist-pin, thereby permitting the slight oscillation of the link 26 necessary to avoid any interference with the free 45 pressing and expanding movement of the spring 12. This swivel joint at the same time affords a reliable coupling between the link and the clamp.

From the foregoing it will be seen that 50 the hinge connections 17 between the clamp collars of the buffer bar and its carrying and cushioning device permits a horizontal angular movement of said bar, such as would occur in encountering an obstacle wholly to 55 one side of the center of the bar, without

producing any breaking strain at either point of connection. Furthermore, by extending the rear connection of the cushioning device to a considerable extent inwardly of the forward ends of the side bars and 70 springs, the jar and vibration imparted to the bar and its attaching devices is considerably reduced, and the danger of the attaching devices working loose is avoided.

It will be manifest to those skilled in the 75 art that the device as shown and described might be considerably varied in details without involving any departure from its principle of operation or sacrificing any of the benefits and advantages secured thereby. 80 Hence I do not limit the device to the particular form and construction disclosed; except to the extent clearly indicated in specific claims.

I claim:

1. An automobile buffer, comprising in combination a buffer-bar, cushioning devices carrying said buffer-bar pivoted on the hinge-bolts of the elliptic springs of the vehicle, and collars embracing said buffer-bar and connected by vertical hinge joints to the forward ends of said cushioning devices, substantially as and for the purpose described. 90

2. An automobile buffer, comprising in combination a buffer-bar, cushioning devices carrying said buffer-bar pivoted on the hinge-bolts of the elliptic springs of the vehicle and extending rearwardly thereof, and links adapted to interchangeably connect the rear ends of said cushioning devices with either the side bars of the vehicle or the underlying elliptic springs pivoted to said side bars, substantially as described. 95

3. An automobile buffer, comprising in combination a buffer-bar, cushioning devices carrying said buffer-bar pivoted on the hinge-bolts of the elliptic springs of the vehicle and extending rearwardly thereof, and links adapted to connect the rear ends 100 of said cushioning devices with the front portion of the vehicle, said links comprising vertical rods having horizontally bent lower end portions screw-threaded to adjustably engage internally threaded holes in the rear ends of said cushioning devices, substantially as described. 110

4. An automobile buffer, comprising in combination a buffer-bar, cushioning devices carrying said buffer-bar and each comprising essentially a bar pivotally mounted on the hinge-bolt of the elliptic spring of the vehicle and extending rearwardly thereof, a guide sleeve rigid with said bar, a plunger rod slidably mounted in said guide sleeve and connected at its forward end to said buffer-bar and a cushioning spring surrounding said plunger rod and abutting against the forward end of said guide-sleeve, and link connections between the inner ends 120 125 130

- of said cushioning devices and the front portion of the vehicle, substantially as described.
5. An automobile buffer, comprising in combination a buffer-bar, cushioning devices carrying said buffer-bar pivoted on the hinge-bolts of the elliptic springs of the vehicle and extending rearwardly thereof, upwardly extending links flexibly connected 20 at their lower ends to the rear extensions of said cushioning devices, and eye-bolts mounted in the forwardly projecting side bars of the vehicle and adjustably engaging the upper ends of said links, substantially as 25 described.
- 10 6. An automobile buffer, comprising in

combination a buffer-bar, cushioning devices carrying said buffer-bar pivoted on the hinge-bolts of the elliptic springs of the vehicle and extending rearwardly thereof, upwardly extending links flexibly connected 20 at their lower ends to the rear extensions of said cushioning devices, and eye-bolts mounted in the forwardly projecting side bars of the vehicle and adjustably engaging the upper ends of said links, substantially as 25 described.

ALLAN L. McGREGOR.
